EMESIS BASIN

Anna Catherine Laubsch, S. Orchard Road,
Vineland, N.J.

Filed May 15, 1963, Ser. No. 74,893

Term of patent 14 years

(Cl. D83—1)

FIG. 2.

FIG. 1.

FIG. 3.

FIG. 4.

FIG. 6.

FIG. 7.

FIG. 5.

FIGURE 1 is a top plan view of an emesis basin embodying my new design;

FIG. 2 is a perspective view;

FIG. 3 is a front elevational view;

FIG. 4 is an end elevational view;

FIG. 5 is a cross sectional view taken on the line 5—5 of FIG. 3;

FIG. 6 is a bottom plan view; and

FIG. 7 is a rear elevational view.

I claim:

The ornamental design for an emesis basin, as shown.
